UNITED STATES PATENT OFFICE.

HENRY W. HEESCH, OF ROCHESTER, NEW YORK, ASSIGNOR TO TAYLOR INSTRUMENT COMPANIES, OF ROCHESTER, NEW YORK, A CORPORATION OF NEW YORK.

PEN FOR RECORDING INSTRUMENTS.

Application filed February 25, 1926. Serial No. 90,503.

This invention relates to pens for recording instruments, and has for an object to provide an improved recording pen which will be applicable for use with either upright or depending pen arms; with which the marking spout may, if it becomes clogged, be readily cleaned or opened in a simple manner, and in an instant of time without refilling of the reservoir or removal of the pen from the arm; which will be relatively simple and inexpensive; and which will operate for relatively long intervals without replenishment of the supply of the recording liquid.

Various other objects and advantages will be apparent from the following description of an embodiment of the invention, and the novel features will be particularly pointed out hereinafter in connection with the appended claims.

In the accompanying drawings:

Figure 1 is a side elevation of the free end of a pen arm carrying a pen of the inverted type constructed in accordance with the invention;

Figure 2 is a front elevation of the same;

Figure 3 is a sectional elevation of the same on a somewhat larger scale, the section being taken approximately along the line 3-3 of Figure 2;

Figure 4 is a sectional plan of the same, with the section taken approximately along the line 4-4 of Figure 3;

Figure 5 is a sectional elevation of a portion of the pen, with the section taken approximately along the line 5-5 of Figure 3;

Figure 6 is a side elevation of the free end of a pen arm carrying a recording pen of the erect type and also constructed in accordance with the invention; and

Figure 7 is another elevation of the same.

Referring particularly to the embodiment of the invention shown in Figures 1 to 5, a cup-shaped reservoir 10 is attached by its side wall to an arm or extension 11 which extends beyond an end of the reservoir and carries edge flanges 12 that extend toward one another. These flanges 12 with a face of the arm serve as guides for slidably receiving the free end of a pen arm 13, the latter being shouldered as at 14 to engage the free end of the arm or extension 11 and limit the extent to which the pen arm will slide into the guide formed by the flanges 12. The flanges 12 may also be

slightly punched toward one another, as at 15, to engage with other shoulders 16 on the end of the pen arm 13, for further limiting the sliding movement of the pen arm in the guides formed by the flanges 12.

The projecting end of the arm 11 may also be slit from its free end to its point of connection to the reservoir 10, with the two sections on opposite sides of the slit connected by an integral strip bent into a U shaped bulge or hump 17 (see Figure 1). This slotted end of the arm 11 thus serves as a spring clamp for frictionally gripping the end of the pen arm and detachably confining the reservoir to the pen arm.

In Figures 1 to 3 the reservoir is of the inverted type, that is, it is secured upon the end of a depending pen arm. The upper end of the reservoir 10 is open and its lower end closed. The reservoir is provided in its lateral wall with oppositely disposed apertures 18 for receiving and mounting a pen spout 19. The spout 19 extends through and fills one of the apertures 18 and has a reduced shouldered end 20, which is received in the other aperture 19, with the shoulder fitting against the inner face of the lateral wall of the reservoir. The bore 21 of the spout extends from end to end, and thus is open at both ends exteriorly of the reservoir through which it extends. At an intermediate point within the reservoir the spout is provided with a cut-away portion 22 which extends to the bore and forms a branch connection thereto from the interior of the reservoir.

When the reservoir is filled partially or entirely with a suitable marking liquid or ink, such liquid will enter the bore 21 of the spout and pass along the same to both ends of its ends. The spout extends from the lower part of the reservoir and terminates in a recording or marking end, so that when this marking end is placed against the surface, upon which a record is to be made, and relative movement is caused between the pen and the surface, the marking liquid will leave the bore of the spout or pen and adhere to the surface, so as to leave a permanent record of the relative movement between the pen and surface.

The bore 21 of the spout is preferably very small, so that it is in effect a capillary bore, and therefore, the marking fluid will not run out of the bore under ordinary con-

- ditions even though the bore is open at both ends. When the marking end of the spout engages with the surface, the capillary attraction of the surface for the liquid in the bore causes sufficient of the marking fluid to leave the bore and adhere to the surface, and thus leave the desired mark upon the surface during a relative movement of the pen and surface.
- 10 The surface upon which records are made is frequently paper or other substance which collects dust or small fibers that adhere to the spout and tend to clog it, and when that occurs, it is commonly necessary to
- 15 clean the pen in order to open the bore. I preferably provide a small rod or wire 23 which may be disposed in the bore from end to end, and this wire also extends from the bore at the end of the spout which terminates in the lateral wall of the reservoir, that is, at the end opposite from the marking point. This rod or wire 23 is slightly longer than the length of the bore, and may be normally disposed with one end entirely
- 20 within the bore 21 or just at the marking end thereof.
- 25 The rod or wire is slightly smaller than the bore, so as not to prevent travel of the marking fluid along the bore by capillary action, and in fact the wire will assist this action to some extent by reason of the increased surface available for the capillary attraction, and thus serves to regulate to some extent, the movement of the marking liquid along the bore. When the marking end of the spout becomes clogged for any reason, such as by a thickening of the marking fluid or the collection of small fibers or dust in the bore at the marking end,
- 30 one may very readily open the spout by pushing the rod or wire 23 further through the bore, so as to project beyond the marking end of the bore in order to eject any from the spout clogging matter, and then
- 35 withdrawing the wire into the bore again, after which the pen will function as well as ever.
- 40 The reservoir is cup-shaped in form and may be readily formed by drawing the same from sheet metal, so that the cost of such a marking pen is relatively small. If de-

sired, and as illustrated, the arm 11 which is secured to the cup may extend for approximately the full length of the reservoir and have an aperture in line with the aperture 18 through which the spout extends so as to provide a more rigid mounting for the spout where it leaves the reservoir.

55 In Figures 6 and 7 I have illustrated a similar marking pen but of the upright or erect type in which the arm 11 depends from the reservoir, instead of upstanding therefrom as in Figures 1 to 5, and thus is attachable in a similar manner to the upper free end of the pen arm 13. The parts are 60 otherwise the same as in Figures 1 to 5, and are designated by similar reference characters.

65 It will be obvious that various changes in the details, which have been herein described and illustrated in order to explain the nature of the invention, may be made by those skilled in the art, within the principle and scope of the invention as expressed in the appended claims.

70 I claim as my invention:

75 1. A pen for recording instruments comprising a reservoir having a tubular marking spout extending therefrom, the bore of said spout being open at both ends exteriorly of the reservoir and communicating at an intermediate point with the interior of the reservoir.

80 2. A pen for recording instruments comprising a cup-shaped reservoir having spaced apertures in the lateral wall, a marking spout passing through and secured in said apertures and extending from the reservoir, said spout having a bore extending lengthwise thereof and open at both ends of the spout, and also having a branch passage opening from a point intermediate of its length into the interior of the reservoir to enable the contents of the reservoir to move through the spout, and a wire disposed in the bore of said spout, of slightly smaller diameter than said bore and extending at one end from the bore of the spout to facilitate its manipulation in the spout for ejecting clogging matter.

85 90 95 HENRY W. HEESCH.
